MOTORCYCLE TURN SIGNAL LAMP

Sherman E. Taylor, 3307 N. MacArthur,
Oklahoma City, Okla. 73104

Filed May 16, 1973, Ser. No. 360,679

Term of patent 14 years

Int. Cl. D26—06

U.S. Cl. D48—32 E

FIG. 1 is a side view of a motorcycle turn signal lamp showing my new design, the motorcycle being shown in broken lines for illustrative purposes only;

FIG. 2 is an enlarged side view thereof;

FIG. 3 is an enlarged side view thereof showing the side opposite to the side shown in FIG. 2;

FIG. 4 is an enlarged top view thereof;

FIG. 5 is an enlarged bottom view thereof;

FIG. 6 is an enlarged rear view thereof;

FIG. 7 is a sectional view taken along lines 7—7 of FIG. 2;

FIG. 8 is an enlarged front elevational view thereof.

I claim:

The ornamental design for a motorcycle turn signal lamp, as shown and described.
